TOBACCO PIPE BOWL SCRAPER
ATTACHMENTJerome M. Mayer, Chicago, Ill., assignor of one-
half to Peter A. Muir, Chicago, Ill.

Application January 30, 1936, Serial No. 61,478

5 Claims. (Cl. 206—41)

This invention relates to tobacco pipe scrapers and more particularly to a medium of convenient attachment therefor, although certain features thereof may be employed with equal advantage 5 for other purposes.

It contemplates more especially the provision of a tobacco pipe bowl scraper and a novel medium of attachment therefor to enable its availability to pipe smokers and render such an inexpensive complement to a tobacco container or 10 the like.

It has long been recognized by pipe smokers that a clean tobacco pipe bowl is essential to a refreshing smoke. Further, the unburned tobacco and residue that becomes associated with 15 the surface of the pipe bowl, creates obnoxious tastes and odors that preclude the continued enjoyment to the pipe smoker. It is essential, therefore, that the pipe bowl be cleaned after each 20 use, and it is proposed to provide a convenient accessory to a tobacco container or the like that affords scraping the interior tobacco pipe bowl surface in a convenient and effective manner.

One object of the present invention is to provide 25 a simple and improved scraper for enabling the removal of the unburned tobacco and other residue that remains in the bowl of a tobacco pipe bowl after each use thereof.

Another object is to provide a convenient and 30 effective accessory to a tobacco container that affords the effective cleansing of the interior surface of the tobacco pipe bowl.

Still another object is to provide a convenient and inexpensive device that is effective for cleansing 35 the tobacco pipe bowl and to remove offensive residues that may remain therein after its use.

A further object is to provide an especially convenient and effective accessory to a tobacco container that renders available an effective bowl 40 scraper to the pipe smoker.

A still further object is to provide a simple and inexpensive tobacco pipe scraper that is readily attached and detached from the tobacco container or the like so as to provide a convenient 45 carrying medium therefor without entailing any more inconvenience than occasioned by the presence of the tobacco container.

Still a further object is to provide a tobacco 50 bowl scraper in conjunction with a container or the like so as to serve as a carrying medium therefor and preclude contact thereof with the clothes of the smoker while on his person.

Other objects and advantages will appear more 55 fully from the following description of an il-

lustrative embodiment of the present invention.

In the drawing:

Figure 1 is a perspective view of a container showing a tobacco pipe scraper associated therewith in a manner embodying features of the present invention. 5

Figure 2 is a fragmentary sectional view taken substantially along line II—II of Figure 1.

Figure 3 is a plan view of a scraper utilized in conjunction with a container in a manner illustrated in Figures 1 and 2. 10

Figure 4 is a perspective view of the modified embodiment of the present invention showing the adaptation of a unique tobacco pipe bowl scraper 15 to a closed portable container.

The structure selected for illustration comprises an elongated blade 10 preferably though not essentially stamped or otherwise shaped from flat metallic sheet material to present a substantially rectangular body 11 terminating in an arcuate 20 extremity 12 that defines a portion of the body 11 and serves as an attaching expedient to a container or other device in a manner which will appear more fully hereinafter. The other or operative extremity of the scraper blade 10 comprises an arcuate head 13 of substantial curvature that merges in a straight lineal line or back edge 14 with a corresponding straight side edge 15 of the scraper blade body 11. 25

The arcuate head 13 extends transversely in a 30 direction opposite to the straight back edge 14 thereof to define a lateral nose or tip 16 that merges with the inwardly cut and arcuately shaped neck 17 that is opposite to the straight back edge 14 of the head 13 so as to present a 35 scraping edge of varied contour to enable effective scraping of the different portions of the pipe bowl usually defined by arcuate surfaces presenting different degrees of accessibility.

As shown, the inwardly directed neck 17 merges 40 with an outwardly inclined edge 18 that extends to a straight side edge 19 in parallelism with the side edge 15 defining the shape and size of the tobacco pipe bowl scraper blade 10. It is to be noted that the blade 10 is stamped or otherwise 45 shaped from sufficiently thin metallic sheet metal that affords some degree of resiliency for reasons which will appear more fully hereinafter.

In order that the scraper blade 10 may be grasped with the finger tips when such is disposed on its flat surface, the straight side edges 50 15 and 19 of the scraper body 11 are upturned to present slight flanges 20 and 21, respectively, that impart a curved cross-section along a transverse median line. While the scraper blade 10 can be 55

carried in the pocket in the form described, such is undesirable because of the sharp edges presented by the tip 16 as well as other operative scraping portions thereof that soon would cut the 5 pockets of the user as well as render such unclean and odorous after the tobacco pipe bowl has been scraped therewith. Consequently, the 10 scraper 10 has been found best adapted for association with a container as will appear from the 15 following description.

The container most desirable for adaptation of a tobacco pipe bowl scraper is a metallic can 22 that is usually utilized for conveying tobacco in its present form of marketing for sale to pipe 15 smokers. The tobacco container 22 is usually oblong in configuration and has a correspondingly shaped wall 23 to which a closure 24 is pivotally attached through the medium of hinges 25. For that matter, the closure 24 can be telescopically 20 associated with the peripheral edge of the container wall 23, and either closure expedient may be resorted to as commercial practice may dictate.

The bottom 26 of the container 22 is usually 25 a flat sheet metal having a periphery shaped corresponding with the oblong configuration of the container 22 and the bottom peripheral edge of the latter is angularly flanged as at 27 and inter-engaged with the complementary flange 28 to provide a beaded peripheral edge 29 that hermetically 30 and permanently seals the bottom 26 to the container wall 23 so as to fully enclose the contents and render such accessible only through the removable top closure 24. The usual roughening surface 30 may be provided on the bottom 26 35 of the container 22 for the purpose of igniting matches as is customary in containers of this character.

It has been found that a scraper of the type 40 described supra may be associated with the container 22. In the present embodiment, the scraper blade 10 is somewhat longer than the distance between the confronting surfaces or projections 31 and 32 defined by the flange 28 and the bottom 26. For that reason, it is possible to 45 spring a scraper blade 10 into position with its flatside adjacent the exterior surface of the bottom 26. It is preferred, however, to provide an arcuate depression or notch 33 in the depending projection 31 of the flange 28 so as to enable 50 the inoperative extremity 12 of the scraper blade 10 to be lodged therein.

The other confronting projection 32 need not be 55 correspondingly provided with the depression or notch 33 in that it is found desirable to provide a protecting plate 34 adjacent the exterior surface of the container bottom 26 so as to cover substantially the entire operative extension of the scraper blade body 11. To this end, the protecting plate 34 is provided with a flange 35 60 around the periphery so that it may be rolled and inter-engaged with the flanges 27 and 28 on the container 22 and the bottom 26, respectively. This permanently attaches the protecting plate 34 adjacent the surface of the bottom plate 26 to 65 provide a narrow back on the extremity having the confronting projection 32 to receive the operative extremity 13 of the scraper blade 11 thereagainst.

When the protecting plate 34 is first rolled with 70 the edge 29 of the container 22, it will be disposed in contact with the surface of the bottom 26 so that it is necessary to slightly pry such from said surface to receive the operative extremity 13 of the scraper blade 11. Consequently, the 75 protecting plate 34 precludes contact of the car-

rier's clothes with the soiled operative extremity 13 of the scraper blade 11 as well as provides an attaching expedient in conjunction with the notch 33 provided in the projection of the container. It will be apparent, therefore, that the finger tip grasp of the upstanding curved edges 20 and 21 of the scraper blade 11 need only be manipulated slightly to flex the scraper blade 10 and effect its removal from the container 22 in order to afford its use in scraping the bowl of 10 the tobacco pipe.

In the modified embodiment of the present invention the scraper 10' is of a circular cross-section so that the inoperative extremity 12' may be 15 permanently attached to the interior of a correspondingly curved tubular shank 36. The tubular shank 36 is of cylindrical configuration and has a closed end 37. The scraper 10' with its blade 11' and operative extremity 13' is confined in a tubular casing 38 which is inwardly 20 telescoped relative to the tubular shank 36 to effect frictional inter-engagement and to comprise the container for the scraper 10'. The end 39 of the casing 38 is closed to serve as a complement to the closed shank 36 and constitute 25 a complete enclosure for the scraper 10' which may be attached to the back and closed by means of a resilient spring clip 40.

The resilient spring clip 40 is of usual construction that is customarily found on fountain pens 30 and pencils for vest pocket attachment and it is preferably riveted or otherwise attached by means of a fastener 41 to the casing 38 proximate to the open extremity 42 thereof. The open extremity 42 receives the scraper 10' and telescopes within the scraper curved shank 36. It will thus be apparent that the shank 36 serves as a part of the casing and enables the manipulation of the scraper 10' for cleaning tobacco pipe 35 bowls and the like.

Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. The combination with a container having a bottom marginal flange, of a tobacco pipe resilient scraper blade, said scraper blade being somewhat longer than the distance between confronting portions of a marginal flange of said container, said blade being applied to the exterior of said container and sprung into detachable association with the external marginal flange of said container.

2. The combination with a container having a bottom marginal flange, of a bottom spaced inwardly from said marginal flange, a tobacco pipe resilient scraper blade, said scraper blade being somewhat longer than the distance between confronting portions of a marginal flange of said container, said blade being sprung into detachable association between confronting portions of said marginal flange on said container and comprising a part thereof, said blade being wholly outside of said container and resting against said container bottom.

3. The combination with a container having a bottom marginal flange, of a bottom spaced inwardly from said marginal flange, a tobacco pipe resilient scraper blade, said scraper blade being 75

somewhat longer than the distance between confronting portions of a marginal flange of said container, said blade being sprung into detachable association between said bottom and marginal flange of said container, and a cover plate attached to said container flange in spaced relation to said container bottom to conceal the scraper head of said blade.

4. The combination with a container having 10 a bottom marginal flange, of a bottom spaced inwardly from said marginal flange, a resilient tobacco pipe scraper blade, said scraper blade being somewhat longer than the distance between 15 confronting portions of a marginal flange of said container, said blade being sprung into detachable association between said bottom and marginal flange of said container, and a cover plate attached to said container flange in spaced

relation to said container bottom to conceal the scraper head of said blade.

5. The combination with a container having a bottom marginal flange, of a bottom spaced inwardly from said marginal flange, a resilient 5 tobacco pipe scraper blade, said scraper blade being somewhat longer than the distance between confronting portions of a marginal flange of said container, said blade being applied flat against said container bottom and sprung into detachable association with the marginal flange of said container, and a cover plate attached to said container flange to conceal the scraper head of said blade, said blade having a curved cross-section to enable the finger grasp thereof for effecting 10 detachment from said container.

JEROME M. MAYER.
